UNITED STATES PATENT OFFICE.

WALTER GEORGE PERKS AND HENRY GEORGE MERRICK FLETCHER, OF HAYLE, ENGLAND.

MAGAZINE-CAMERA.

SPECIFICATION forming part of Letters Patent No. 707,156, dated August 19, 1902.

Application filed August 31, 1901. Serial No. 73,905. (No model.)

To all whom it may concern:

Be it known that we, WALTER GEORGE PERKS and HENRY GEORGE MERRICK FLETCHER, subjects of the King of Great Britain, residing at Hayle, in the county of Cornwall, England, have invented certain new and useful Improvements in Magazine-Cameras, of which the following is a full and complete specification, such as will enable those skilled in the art to which it appertains to make and use the same.

The object of this invention is to provide improved means for separating flexible sensitized films in a magazine-camera, said films being usually held in a pack in the camera; and with this and other objects in view the invention consists in a magazine-camera constructed as hereinafter described and claimed.

In the drawings forming part of this specification, in which like letters of reference designate corresponding parts in the several views, Figure 1 is a central vertical section of a part of a camera provided with our improvement. Fig. 2 is a similar view showing the parts of the apparatus in a different position. Fig. 3 is a portion of a section at right angles to that shown in Figs. 1 and 2 and looking forward. Fig. 4 is a similar view showing the parts in a different position. Fig. 5 is a side and opposite end view of the details of the construction, and Fig. 6 a similar view showing a modified form of construction and showing a side and end view thereof.

In the practice of our invention we provide a separating-disk A, which may be of steel or other hard material and which may also be made in various shapes, (shown in Figs. 3, 4, 5, and 6,) and in one edge of this disk is preferably formed a triangular space forming a straight radial tooth or shoulder a, similar to a ratchet-tooth, beveled or sharpened on one side, so as to form an edge, which is bent backward slightly or equal to the thickness of the films to be separated. In Fig. 5 is shown another form of this disk composed of a flat piece (marked A²) having a ratchet-tooth or projection a, the same as hereinbefore described, also a second piece or disk (marked A³) and an intervening disk, (marked A²), which latter may be attached to A or A³ or may

consist of an independent piece, and all of which are firmly attached to the axle B.

In Fig. 6 is shown at A³ another form of disk A with merely a slit formed in the perimeter thereof, the part a² being stamped or bent rearwardly and being also beveled or sharpened.

Referring to Figs. 1 to 4, the axle B is mounted in a frame C, secured to the under side of the top of a camera, near the rear end thereof, and said camera is provided at its rear end with a hinge-door A⁴, the top and bottom portions of said camera being designated by the reference characters A⁵ and A⁶. Mounted on the axle B and working loosely on the same between separate parts of the frame C is a disk E, provided with a pin D, which operates in the hole or slot a³ in the edge of the disk A. The axle B is also provided with a cam composed of two parts H and H', the part H being connected with the frame C and being provided with an arm J, upon which acts a spring K, which controls to an extent the movement of the axle B and insures its being held in a correct position. The axle B is also provided with a spiral spring L, which exerts a pressure on the cam-head H.

Passing through the top of the casing of the camera and vertically movable therein is a slide G, composed of any suitable opaque material, and said slide is provided at the lower end thereof with a thickened portion g, which fits in a transverse cavity or recess g² in the bottom of the camera-casing, and the rear face of the said slide is provided at the bottom thereof with a thickened portion g⁶, in which is formed a bayonet-slot F in such position that as the slide is pulled up the pin D enters said bayonet-slot and comes in contact with the bottom of said slot and causes the disk A and axle B to revolve to the required extent, as shown in Figs. 1 and 3, and the frame C is also provided with stops T' and T² to prevent the axle B from revolving too far.

Pivoted to the opposite sides of the casing of the camera, as shown at P, are two levers O, and these levers are provided with edges which are adapted to bear against the shutter G when said levers are in an upright po-

sition, thus leaving a suitable space between the slide G and the body portions of said levers to receive the film, said film being shown at M' in Fig. 2. The lower ends of the levers 5 O are loosely connected at O² with a horizontally-movable slide O³, and these levers when the slide G is in its raised position, as shown in Fig. 1, are normally held in the forwardly-directed position by a double spring O⁴, which 10 operates in connection with lugs or projections O⁵, formed on or secured to ears O⁶, through which the pivot-pins P of said levers pass. When the slide G is depressed, the bottom portions of these levers are moved forwardly 15 thereby and the slide O³ moves with them.

In the back portion of the camera-casing is placed a follower S, the upper end of which is provided at each side with a pin S², and 20 these pins rest on guide-strips S³, and similar guide-strips S⁴ are placed below the guide-strips S³ and serve to guide the follower S and hold it out of contact with the sides of the casing of the camera, and between the follower S and the back portion or hinged door 25 A⁴ of the camera-casing is placed a spiral spring N, which forces the follower S forwardly. The front lower edge of the follower S is beveled backwardly, as shown at S⁵, and 30 the pins S² support the follower and prevent it from dropping onto the slide O³. The slide G in its operation passes through the slide O³, which is provided with an opening for this purpose, and the object of this slide is to prevent 35 the films M from creating too much friction on the bottom of the casing of the camera. The films then are placed in a pack in the position shown in Fig. 2, between the follower S and the slide G, and rest on the slide O³, and in operating the apparatus the said 40 slide G is pulled up, as shown in Fig. 1. In this operation the pin D will engage the groove F in the bottom of the said slide and will revolve the disk A, causing the tooth or projection a, which is provided with a knife-edge, to enter the space between the first film and the remainder of the pack and to separate the first film from the said pack. In 45 this operation the lever O assumes the position shown in Fig. 1, and the first film M' drops forwardly, as shown in said figure, and after the slide G is depressed the separating-disk A resumes its first position, or that shown in Fig. 1, and as the slide G descends and passes into the position shown in 50 Fig. 2 the levers O also assume the position shown in Fig. 2, and the rear edges thereof press against the slide G and the film M' rests on the shoulder or projection g⁴ at the bottom of said slide, and all the parts, including the slide O³, will also assume the position shown in Fig. 2, and the film M' is in position for exposure. On again raising the slide G the shoulder or projection g⁴ at the bottom 55 thereof will throw up or lift the film M', which is thrown into the compartment Z at the top of the camera-casing, said film being guided

into this compartment by a working spring W, secured to the bottom surface of the camera-casing and so formed as to bear on the front pieces of the slide. The compartment Z is provided with an opening at Z², at the bottom of which is a curved plate Z³, which also serves to guide the film M' thereinto. Secured to the bottom of the top of the camera-casing are springs W², and these springs when the said slide is drawn upwardly also strike on the shoulder or projection g⁴ and prevent the said slide from being withdrawn from the casing. When the slide G is depressed, as shown in Fig. 2, the spring L on the shaft or axle B is depressed; but when said slide is moved upwardly, as shown in Fig. 1, this spring is expanded and forces the disk A forwardly, thus enabling the apparatus 85 to operate, as hereinbefore described.

The disks A² and A³ (shown in Figs. 5 and 6) will operate in the same manner as the disk A, (shown in Figs. 1 to 3, inclusive,) and our invention is not limited to the form of the slide G nor to the various parts thereof, as many changes in the form and construction of this slide, as well as in the form and construction of the other parts of the apparatus herein shown and described, may be made 95 without departing from the spirit of our invention or sacrificing its advantages.

Having thus fully described our invention, what we claim as new, and desire to secure by Letters Patent, is—

1. In a magazine-camera comprising a casing, a vertically-movable slide mounted therein, a follower mounted rearwardly of said slide, an axle mounted above said follower and a separating-disk connected with said axle and means whereby the axle is turned in opposite directions as the slide is raised and lowered, substantially as shown and described.

2. In a magazine-camera, a casing, a vertical and movable slide mounted therein, levers pivoted in front of said slide, a horizontal slide pivotally connected with the lower ends of said levers and through which the first-named slide is adapted to pass, means whereby the levers are held in a forwardly-directed position when the vertical slide is raised and in a backward position when said slide is lowered, devices for holding a pack of films adjacent to the back of the vertical slide and for pressing the same forwardly, an axle mounted above said devices, a separating-disk connected with said axle and devices whereby said axle is turned in opposite directions as the vertical slide is raised or lowered, substantially as shown and described.

3. In a magazine-camera, an axle, a separating-disk connected therewith, a vertical slide mounted in front of said axle, and devices whereby said axle is turned in opposite directions as said slide is raised or lowered, substantially as shown and described.

4. In a magazine-camera, a casing, a vertical and vertically-movable slide mounted

therein, a horizontal slide mounted beneath said first-named slide, means for holding said levers in an upright position and against the vertical slide when the latter is in its lowest 5 position and for holding said levers in a forwardly and upwardly inclined position when the vertical slide is in its raised position and means for pressing a pack of films against the back of said slide and for separating one of 10 said films from said pack when said slide is raised, substantially as shown and described.

5. A magazine-camera provided with a specified vertical and vertically-movable slide G, a follower S, a horizontal slide O³, levers pivotally connected with the front of said horizontal slide, an axle B mounted above said follower and movable forwardly and backwardly, a separating-disk connected with the front end of said axle and devices for turning 15 said axle in opposite directions as said first-named slide is raised or lowered, substantially as shown and described.

6. A magazine-camera provided with a suitably-supported axle, a separating-disk A con-

nected therewith, means for turning said axle 25 in opposite directions, a cam connected partly with said axle and partly with the support thereof, and a spring L mounted on said axle, substantially as shown and described.

7. In a magazine-camera, a casing, a vertically-removable slide mounted therein, devices for supporting a pack of films back of said slide and pressing the same forwardly, an axle mounted above said devices and provided with a separating-disk and devices for 30 turning said axle in opposite directions as the slide is raised or lowered, substantially as 35 shown and described.

In testimony that we claim the foregoing as our invention we have signed our names, in 40 presence of the subscribing witnesses, this 19th day of August, 1901.

WALTER GEORGE PERKS.
